UNITED STATES PATENT OFFICE.

EDWARD POSSON, OF CHICAGO, ILLINOIS.

TRAP AND DRAIN FOR RAILWAY-CARS.

1,329,015.

Specification of Letters Patent. Patented Jan. 27, 1920.

Application filed October 14, 1916. Serial No. 125,699.

To all whom it may concern:

Be it known that I, EDWARD POSSON, a citizen of the United States, residing at Chicago, in the county of Cook and State 5 of Illinois, have invented certain new and useful Improvements in Traps and Drains for Railway-Cars, of which the following is a specification.

This invention relates to drains for rail- 10 way cars, particularly refrigerator cars, and its purpose is to provide an improved device of this kind which may be constructed eco- nomically and which will operate efficiently.

In the construction of refrigerator cars it 15 is desirable to prevent the free entrance of outside air into the interior of the car, and it is also necessary to provide means for carrying away the moisture which is produced by the melting of the ice in the ice 20 chambers of the car. An important object of this invention is to provide an improved trap and drain for conducting away the moisture which collects within the car, while at the same time preventing the free en- 25 trance of air into the car through the drain. Another important feature of the invention is the provision of a double drain, embodying a principal drain connection through which the water normally escapes from the 30 interior of the car, and an auxiliary drain opening through which the water automatically escapes when the principal drain opening becomes clogged by dirt or other foreign materials which collect with the moisture 35 in the car. A further object is to provide a drain embodying improved means for removing foreign materials which may clog the same and improved means for permitting access to the same for cleaning and re- 40 pairing. Another feature is the provision of a drain embodying means for conducting the moisture away from the walls and other associated parts of the car. Other objects relate to various features of construction and 45 arrangement to be hereinafter described.

All of the objects of this invention will appear more clearly from the following specification, taken in connection with the accompanying drawings, in which one em- 50 bodiment of the invention is illustrated.

In the drawings—

Figure 1 is a perspective view of a section of a car showing my improved drain in operative position. 55 Fig. 2 is a plan view of the trap and drain with parts broken away.

Fig. 3 is a vertical section through the drain, taken transversely of the car.

Fig. 4 is a detail sectional view, taken on the line 4—4 of Fig. 3.

Fig. 5 is a sectional view, taken longitudinally of the car on the line 5—5 of Fig. 3.

Fig. 6 is a detail sectional view, taken on the line 6—6 of Fig. 3; and

Fig. 7 is a detail view of the hinged clo- 65 sure for the lower part of the auxiliary drain.

Referring to the drawings, the numeral 10 designates the side sill of a refrigerator car, this side sill composing a part of the under- 70 frame of the car which is carried by the usual running gear comprising the wheels 11. The floor of the car is designated by the numeral 12, and above this floor there is mounted an auxiliary or sub-floor 13, 75 which is composed of a plurality of trans- verse supporting members 13^a mounted on the longitudinal members 13^b and carrying the longitudinal spaced apart members or slats 13^c. This sub-floor forms a ventilating 80 floor through which the cold air can pass upwardly to the refrigerating chamber 14 of the car, it being understood that the cold air proceeds through the space beneath the sub-floor and the main floor from the ice 85 bunker air chamber 15, one of which is usually located at each end of the refrigerator car. The ice chamber 15 also has a sub-floor 16, which comprises the members 16^a, 16^b and 16^c and is in all respects similar 90 to the sub-floor 13 of the chamber. The ice chamber is separate from the refrigerating or packing chamber of the car by any suitable form of bulkhead or partition; in the present instance I have illustrated the lower 95 part 17 of the bulkhead as being formed of a wire screen 17^a carried by a metal frame 17^b of Z-bar form and having adjacent the end thereof an aperture 17^c through which access may be had to my improved trap and 100 drain. This screen permits the cold air to pass from the lower part of the air chamber to the lower part of the refrigerating cham- 105 ber of the car in which the perishable goods are stored for shipment. These features *per se* do not constitute a part of the present invention, since my improved drain may be embodied in various forms of refrigerator car construction, such, for instance, as that shown and described in my co-pending ap- 110 plication, Serial No. 114,783 filed Aug. 14, 1916, and the foregoing features have been

illustrated for the purpose of showing the adaptation and advantages of the present invention.

My improved drain comprises a casing 20 formed of malleable iron, or the like, having an upper enlarged part 20^a which forms a water chamber or drain trap 21, into which the water flows after collecting on the floor of the ice chamber. This part 20^a is provided with an annular flange 20^b which is adapted to seat upon the metal lining 22 of the ice chamber around the aperture in the floor in which the casing is seated, being secured thereto by suitable rivets 23 and soldered around the joints as shown at 24. The sub-floor 16 of the ice chamber is seated upon the metal lining 22, and the water which collects when the ice melts flows along the metal lining of the floor and collects in the trap 21 of the casing. If desired, one of these drains may be provided at each side of the car for each ice chamber, and it will be understood that the floor of the ice chamber is so inclined as to effect the proper draining of the moisture into the trap or traps 21 of the drains.

The casing 20 is seated in a chamber formed in the floor of the car between the longitudinal sills 25 and between the transverse sills 26, which sills support the floor 12 and between which the heat insulating sheets 26^a are mounted. The lower part of this chamber is closed by the metal plate 27, which is secured to the framework of the car and which is provided with a suitable aperture to receive the downwardly extending circular part 20^c of the casing. An asbestos sheet 27^a is preferably seated on the plate 27. The chamber so formed is filled with suitable heat-insulating material 27^b, such as asbestos, hair, or the like.

Formed integrally with the lateral walls of the trap 21, and extending longitudinally of the car between said walls, is a depending flange 20^d which terminates a short distance above the lower wall of the trap and which is spaced from the adjacent parallel wall of the trap. This parallel wall is provided with a boss 28 having a threaded aperture therein which is engaged by the drain pipe 29. This drain pipe is inclined downwardly and extends outwardly through the side wall of the car, projecting a slight distance beyond the side wall which is reinforced by a plate 30 having an aperture therethrough to receive the pipe. An agitating member 31 is mounted in the pipe and has an angularly disposed handle 31^a at the outer end of the drain pipe to be engaged by the hand of the operator. The rod 31^b of the agitating member extends inwardly through the pipe 29 and through a suitable aperture in the flange 20^d, where the projecting end is engaged by a nut 32, held in position by a pin 33. A washer 34 is mounted between the

nut and the flange 20^d. An agitating arm or finger 31^c is fixed on the rod 31^b and extends transversely thereto, being directed in a downward direction when the agitating member is in its normal position. The water which collects in the trap will rise until it reaches the level of the lowermost part of the inner end of the drain pipe, whence it will flow outwardly and drop down at the side of the car. Should dirt, or any other foreign material, clog the space between the flange 20^d and the mouth of the pipe 29, the agitating member 31 may be manipulated to stir up the clogged material and cause the water to carry it away through the drain.

In addition to the principal drain opening described above, I have provided an auxiliary drain opening, which is formed by the flange 20^e of the casing extending upwardly from the lower wall of the trap 21 as a continuation of the part 20^c. The upper end of this sleeve 20^e terminates a short distance above the level of the lowermost part of the inner end of the drain pipe, 90 so that the water collecting in the trap normally flows out through the pipe 29; but when such pipe becomes clogged the water will well up to a greater height and will then pass downwardly through the auxiliary drain opening formed by the annular sleeve and associated parts. The mouth of this sleeve is closed by a drain cap 35, which is hinged on the projecting lug 36 of the casing by means of a pin 37. The end of the cap opposite the pin 37 is engaged by a downwardly-extending pin or post 38, which engages the lower wall of the trap 21 opposite the hinge, and thus maintains the cap 35 in normal horizontal position spaced 105 upwardly from the mouth of the sleeve 20^e. It will be seen that the cap comprises an annular downwardly-extending flange 35^a, which surrounds and is spaced outwardly from the upper part of the sleeve. It will 110 be seen, therefore, that after a small amount of water has collected in the trap the openings therefrom will be sealed by the water to prevent the entrance of air into the interior of the car through the drain. For 115 this purpose the lower edges of the flanges 20^a and 20^d terminate below the lowermost part of the inner end of the drain pipe 29, so that there is always sufficient water in the trap to effect an air-tight seal. Two of 120 the lugs 36 are provided, being located opposite each other in a plane extending longitudinally of the car, so that the cap may be pivoted on either lug in order to direct the free end of the cap toward the interior of 125 the car when the drain is located at either end of the car. In this way the cap may be reached through the aperture 17^c in the bulkhead and swung away from the operator to permit cleaning.

The downwardly extending part 20^c of the casing 20 projects through the plate 27, as above described, and is connected at its lower end to a supplementary casing 40. This connection is made by means of the parallel flanges 41 formed on the part 20^c and arranged to be engaged by the guide-ways 42 formed integrally with the upper part of the supplementary casing. After the supplementary casing has been moved into position on the flanges 41 of the main casing, the two parts may be locked in position by means of a pin 43 which passes through the lug 44 carried by the casing 40 and through alining apertures in the parallel lugs 45 carried by the casing 20. This pin may preferably be a split pin which will permit the ready removal of the lower part of the casing when desired.

The supplementary casing 40 has the lower part thereof angularly disposed with respect to the part 20^c of the main casing, and the upper side thereof is open, as shown at 46, this opening forming a continuation of the corresponding opening 46^a formed in the outer side of the part 20^c. The lower wall of the supplementary casing 40 directly below the part 20^c is provided with an opening 47 which is normally closed by a cover 49 pivoted on the casing by means of a pin 50, which passes through the walls of an outwardly extending projection 51 formed on the casing and through a suitable aperture formed in the arm 49^a carried by the cover. This cover is normally held in position by gravity on the flange 53 around the opening 47, but it may be pushed upwardly by a suitable instrument into the position shown by dotted lines at 49^b, thus permitting access to the interior of the main casing, so that the cover 35 may be lifted if desired, in order to effect the removal of waste matter which may have collected in the trap, for instance, or for any other desired purpose. When in its uppermost position, the ribs 49^c of the cover will pass into the grooves 57, which are formed in the projecting parts 45 of the main casing. When the cover is released by the operator it will automatically fall into its normal closed position, and when the cap 35 is released by the operating instrument it will also fall by gravity to its normal position over the flange 20^c. A sheet metal chute 55, open on the upper side, is attached by rivets 56 to the outer end of the supplementary casing, and is adapted to direct the water passing downwardly through the drain outwardly to a point adjacent the plane of the side wall of the car. In this way the moisture is conducted away from the walls and the various parts of the rolling stock of the car.

From the foregoing description it will be seen that I have provided an improved double drain, embodying one drain outlet which

is adapted to operate normally for the purpose of conducting away the water which collects in the trap of the drain, and embodying a supplementary drain opening which is adapted to function when the first-named drain becomes inoperative by reason of being clogged, for instance. When the first-named drain becomes clogged, the agitator may be manipulated to remove the waste material which causes the clogging, and the principal drain will then operate normally, while the supplementary drain will discontinue to operate. By this means it is certain that one of the drain openings will be operating constantly, and if a passing trainman notices that the principal drain is not performing its function, the agitator may be manipulated to restore the apparatus to its normal operation. It will be seen that the trap may be readily cleaned through the aperture 17^c in the bulkhead, and also the supplementary drain opening, by means of the removable covers 35 and 49, which I have provided for that purpose. It will further be apparent that each of the drain openings conducts the waste water to a point where it will not fall on the running gear of the car.

Although I have shown and described a particular embodiment of the invention for purposes of illustration, it will be understood that it may be constructed in various other forms without departing from the spirit of my invention as embodied in the appended claims.

What I claim is:

1. In a drain for a railway car, a receptacle mounted in the floor of the car, an angular conduit leading downwardly from said receptacle through said floor and outwardly toward the side of said car, a removable cap in said receptacle over the upper end of said conduit, and a removable plate in the wall of said conduit to permit removal of said cap from a position beneath said car.

2. In a drain for a railway car, a receptacle mounted in the floor of the car, a conduit leading downwardly from said receptacle through said floor, a removable cap over the upper end of said receptacle, means to permit removal of said cap from a position beneath said car, and a second drain conduit leading from said receptacle at a lower level than the inlet opening of said first-named conduit.

3. In a drain for a railway car, a receptacle mounted in the floor of the car, a partition across said receptacle forming a chamber opening adjacent the bottom of said receptacle beneath the level of fluid therein, an outlet conduit opening above the bottom of said receptacle, and a second outlet conduit opening from said chamber below the level of said first-named outlet.

4. In a drain for a railway car, means within the car for collecting fluid therein, a conduit leading from said collecting means to the exterior of said car, and means operable from the exterior of said car for restoring the operation of said conduit after it has become inoperative.
5. In a drain for a railway car, means within the car for collecting fluid therein, a conduit leading from said collecting means to the exterior of said car, an operating member mounted in said conduit, and means carried by said operating member at the inner end of said conduit for removing materials from the mouth of said conduit.
6. In a drain for a railway car, a receptacle having a chamber for collecting fluid, said receptacle having a partition across the same forming a second chamber communicating with said fluid collecting chamber beneath the level of fluid therein, a fluid outlet from each of said chambers communicating with said chambers at different levels, and means controlled from the outside of said car for agitating the contents of said chambers.
7. In a drain for a railway car, a receptacle having a chamber for collecting fluid, said receptacle having a partition across the same forming a second chamber communicating with said fluid collecting chamber beneath the level of fluid therein, a fluid outlet from each of said chambers communicating with said chambers at different levels, and a hinged cap over the outlet from said first-named chamber, said cap being spaced upwardly from the mouth of said outlet and outwardly from the walls thereof.
8. In a device of the class described, a member having a chamber for collecting fluid, a drain conduit leading from said chamber, a second conduit leading from said chamber, the inlet opening of said last-named conduit being at a higher level than the opening of said first-named conduit, and covers for the inlet openings of each of said conduits.
9. In a drain for a railway car, a casing having a chamber formed therein, said chamber being open on its upper side to permit water to flow therein from the floor of said car, an outlet conduit having the walls thereof projecting upwardly from the bottom of said casing, a cap for said conduit spaced upwardly from the mouth thereof and having a flange extending around and outwardly from said conduit, a permanent opening being formed between said flange and the lower wall of said chamber, and a second drain conduit leading from said casing above the lower edge of said flange.
10. In a device of the class described, a casing having a fluid collecting chamber formed therein and a supplementary chamber in communication with said first-named chamber, an outlet conduit leading from said supplementary chamber, a second conduit having its walls projecting upwardly from the lower wall of said fluid collecting chamber, and a cap over said second-named conduit, said cap having a flange extending around and outwardly from said second-named conduit, the lower edge of said flange and the communication between said fluid collecting chamber and said supplementary chamber being below the level of the mouth of said first mentioned conduit.
11. In a drain for a railway car, a receptacle arranged to be mounted in the floor of the car to collect fluid therein, an outlet duct leading downwardly from said receptacle, a movable cap mounted over the upper end of said duct in said receptacle, said duct having an aperture in its lower wall beneath the floor of said car, and a movable cover over said aperture, whereby a rod may be thrust upwardly through said aperture to remove said cap from its position over the upper end of said conduit.
12. In a drain for a railway car, a receptacle for fluid adapted to be mounted in the floor of the car, an outlet duct leading downwardly from said receptacle, a supplementary casing detachably connected to said duct, and a chute connected to said casing and extending outwardly from the side of said car.

In testimony whereof I have subscribed my name.

EDWARD POSSON.
